ATTORNEY.

UNITED STATES PATENT OFFICE.

CHARLES W. GREEN, OF CHICAGO, ILLINOIS, ASSIGNOR TO LOUISA E. GREEN,
OF SAME PLACE.

FOLDING BED.

SPECIFICATION forming part of Letters Patent No. 351,320, dated October 19, 1886.

Application filed February 26, 1886. Serial No. 193,314. (No model.)

To all whom it may concern:

Be it known that I, CHARLES W. GREEN, a citizen of the United States, and a resident of Chicago, county of Cook, and State of Illinois, 5 have invented new and useful Improvements in Folding Beds, of which the following is a specification, reference being had to the accompanying drawings, illustrating the invention, in which—

10 Figure I is a plan or top view of a folding bed embodying my invention; Fig. II, an enlarged end elevation of Fig. I. Fig. III represents the bed as folded; Fig. IV, a broken sectional longitudinal elevation of the bed. 15 Fig. V represents the end posts removed from the other posts.

This invention relates to means for converting an ordinary woven-wire mattress into a folding bed.

20 The invention, in brief, consists in pivoted cross-legs, whose lower ends are spread apart to give proper support to the mattress, and shut together and the mattress swung vertically between the two sets of legs when the 25 bed is folded, suitable mechanism being employed to serve as a side and end inclosure for the bedding, and also for manipulating the parts and supporting them both in bed form and folded shape, as the same is hereinafter 30 fully described and shown.

F G E represent an ordinary woven-wire mattress, which I find to be the best form of bottom now known to put in my folding bed.

35 Surrounding the side and end pieces, F G, of this mattress-frame is attached by screws or otherwise a box-frame, I H, of suitable lumber, for the purpose of inclosing the bedding to be used, the frame for ordinary bedding being about eight inches high above the side rails,

40 F. The bed thus constructed is supported by two sets of adjustable cross-leg supports, A A. That these legs may be properly opened to support the bed-bottom for occupancy and closed for the bottom to be folded, and properly locked into each other, ordinarily to support the bottom at a given height, diagonal gains K K (more clearly shown at Fig. V) are formed in the two inner faces of the two pieces A, forming each pair or set of legs, whereby 45 both pieces lie in the same plane, and, when

open, to support the bed-bottom, the edges of the pieces A A, respectively, bear against the shoulders c c of the other piece, and in so doing occupy the position shown at Figs. I and II.

It will be seen that the gains K are quite inclined—that is, the cross-legs may be shut together, as shown at Fig. III. The mattress is supported on the cross-legs A A by means of headed bolts D L, which lie under the end rails, G, and are secured in those positions by ordinary staples, M M, put over the shanks of the bolt and driven into the under side of the rails. The heads L of the bolts bear against the inner edges of the rails, so that the nuts C may be sufficiently turned up to hold the parts together. This mode of fastening becomes necessary, because the end rails cannot safely be weakened by bolt-holes made through them. The bolts pass through holes b b in the legs and also through a suspended support, B, at 7c each end of the bed. When the bed has unusual weight placed thereon, the supports B will be brought to the floor, and thus relieve the legs A A from such excessive strain as they otherwise would be subjected to. From 75 this it will be seen that the two sets of legs have no central connection, except by means of the mattress-frame and bolts D L, and no other connection, except by the support J, low down on the legs. There is left an unobstructed 80 space between the sets of legs for the mattress-frame to be turned to a horizontal position or a vertical position, as required.

To make the mattress rigid with the legs when the bed is in position for use, hooks W 85 are employed, one at each end of the bed, and pivoted to one of the leg-pieces A at f, and made to engage a catch or pin, g, on the end of the mattress-frame. Without these hooks or other suitable connections the bed cannot 90 be used. To hold the legs in a folded form, a latch, N, is pivoted to each set of legs at P, and is made to engage a catch-pin, O, in the opposite leg, as more clearly shown at Fig. III. I find it better to slot the upper ends of the 95 legs and insert the latches N in the slots than to attach the latches to the sides of the legs. The bed is to be folded by grasping it by the hand at R. This will bring the legs together, after which the catch W is to be detached from 100

pin *g* and the latch *N* connected with the pin *O*, as shown, and the bed will then occupy the position shown at Fig. III. A curtain, *S*, can then be hung to the upper side rail, *F*, to conceal the bed-frame, and it can be extended around the ends to cover all the structure in substantially the same manner as is the custom now on other folding beds.

Having thus described my invention, what I claim as new, and desire to secure by Letters Patent, is—

1. In folding beds, the two sets of cross-legs *A A A A*, pivoted centrally together and to the middle portions of the ends *G* of the mattress-frame by a single bolt, *D L*, at each end, constructed and attached as specified, in com-

bination with a mattress-frame hung to swing to a vertical position between the legs and held in that position with the legs by means of the latch *N*, and the catch or hook *W* to hold the mattress-frame in a horizontal position, as specified.

2. The two sets of cross-legs *A A A A*, pivoted together and to the mattress-frame by bolts *D L*, in combination with the supports *B B*, hung to said bolts, as and for the purpose specified and shown.

CHARLES W. GREEN.
